UNITED STATES PATENT OFFICE

JOSEPH WALTER, OF CALUMET CITY, ILLINOIS, ASSIGNOR TO FRANK S. BETZ COMPANY,
OF HAMMOND, INDIANA, A CORPORATION OF INDIANA

NURSERY BED

Application filed June 3, 1929. Serial No. 363,093.

This invention relates to nursery beds and more particularly to those used in hospitals and other institutions for new born infants.

During the first twenty-four hours after birth, an infant should lie on an incline with its feet at a higher elevation than its head. This position is necessary to assist the heart action and to prevent the aspiration of mucus from the trachea into the lungs by facilitating the drainage. In this position the infant is also less apt to choke after a regurgitation.

After the first twenty-four hours following birth, it is frequently desirable to elevate the child's head instead of its feet as, for instance, where it is necessary to prevent regurgitation following a feeding.

Nursery beds in common use consist of an upright frame, on which is supported a removable basket. Heretofore when it is necessary to support the basket in an inclined position, the nurse propped up one end of the basket with a blanket or some other available article.

The main objects of this invention are to provide a nursery bed having improved means for supporting the basket; and to provide improved supporting means of this kind which are adjustable for elevating either end of the basket with respect to the bed frame.

An illustrative embodiment of this invention is shown in the accompanying drawings, wherein:

Figure 1 is a side elevation of an improved bed.

Fig. 2 is an enlarged horizontal section, taken on the line 2—2 of Fig. 1, with the basket removed.

Fig. 3 is a fragmentary section, taken on the line 3—3 of Fig. 2 and showing one end of the basket elevated.

Fig. 4 is a view similar to Fig. 3 but showing the opposite end of the basket elevated.

Fig. 5 is an enlarged detail in section, taken on the line 5—5 of Fig. 3.

In the form shown, the bed comprises a basket 1 supported on an upright frame 2 having casters 3 to permit trundling of the bed.

The removable basket 1 may be made of metal bands or of any other suitable material.

In the construction illustrated, the frame 2

comprises an upper rim formed of angle bars 4 secured to upright legs 5, which are braced by cross bars 6 and a longitudinally extending bar 7 adjacent the lower ends of the legs.

Secured to the angle bars 4, are brackets 8 for supporting buffer pads 9, which project inwardly to prevent the basket 1 from coming into contact with the rim of the frame.

Mounted on the frame, is an improved basket support comprising a pair of substantially parallel side sections, to which is hinged a pair of supporting members adapted to be rocked into positions for elevating either end of the basket. The side sections are secured to the legs 5 on respectively opposite sides of the frame 2 and, in the form shown, each side section comprises an inner rack bar 10, an intermediate brace 11 and an outer bar 12.

The upper edges of the bars 12 are bent inwardly to form horizontal supporting ledges 13, which are spaced from the upper edges of the bars 10 in which are formed racks 14. Secured to the two side sections, is a pair of centrally located pins 15, to which the two supporting members are hinged.

In the form shown, each of the supporting members comprises a pair of substantially parallel arms 16 hinged to the pins 15 and supporting at their free ends a cross bar 17, on which is mounted an anti-friction roller 18 for supporting the basket 1. The ends of the bar 17 project outwardly for engagement with the supporting ledges 13.

Hinged to each of the supporting members, is a substantially U-shaped bracket adapted for engagement with the rack bars to retain either end of the basket in various elevated positions. In the form shown, each of the retaining brackets comprises a pair of links 19 hinged on the bar 17 and supporting a rod 20 at their outer ends. The ends of the rod 20 project outwardly for engagement with the racks 14.

Extending between the links 19 of each supporting member, is a brace 21, which is located between the rod 20 and bar 17. The rod 20 and brace 21 of each supporting member form a suitable handle which may be grasped in one hand for raising the bar 17 out of con-

tact with the ledges 13 and for shifting the rod 20 into engagement with the desired notches of the racks.

In operation, to support the basket 1 in a horizontal position, the bars 17 are both lowered so as to rest on the ledges 13. When it is desired to elevate one end of the basket, the corresponding bar 17 is raised. To raise the bar 17, one hand of the operator is placed 10 underneath the rod 20 with the palm bearing against the rod and the tips of the fingers bearing against the lower face of the brace 21. By pressing upwardly with the fingers on the brace 21, the bar 17 is lifted away 15 from the ledges 13 and the rod 20 is then moved inwardly by the pressure of the palm of the hand so as to move the ends of the rod 20 into engagement with the desired notches.

Although but one specific embodiment of 20 this invention has been herein shown and described, it will be understood that numerous details of the construction shown may be altered or omitted without departing from the spirit of this invention as defined by the 25 following claims.

I claim:

1. A nursery bed comprising an upright frame, a pair of arms hinged on said frame on a horizontal axis, a cross bar mounted on 30 the outer ends of said arms, a removable bed basket supported on said cross bar, racks on said frame, a substantially U-shaped bracket hinged on said cross bar and movable into engagement with said racks for elevating said 35 bar to raise one end of said basket, and a cross brace secured to the sides of said bracket and located between said cross bar and the base of said bracket, said cross brace and the base of said bracket being adapted to serve as a handle for use in raising and lowering said cross bar.

2. In a nursery bed, an upright frame comprising supporting legs, a pair of horizontal side bars secured to said legs and disposed in 45 substantially parallel spaced relation to each other, racks formed on said bars, a pair of braces secured to said legs and arranged on respectively opposite sides of said bars in close proximity thereto, the upper edges of 50 said braces extending inwardly to form horizontal supporting ledges, a pair of arms hinged on said bars, a horizontal rod mounted on the outer ends of said arms, the extremities of said rod projecting outwardly 55 beyond said arms and being adapted to rest upon said supporting ledges, and a substantially U-shaped bracket hinged on said arms and adapted to engage said racks for retaining 60 said rod in an elevated position.

60 Signed at Hammond this 31st day of May, 1929.

JOSEPH WALTER.
